UNITED STATES PATENT OFFICE.

HENRI W. BILTZ, OF KANSAS CITY, MISSOURI.

ATTACHMENT FOR MAILING-MACHINES.

1,110,666.

Specification of Letters Patent. Patented Sept. 15, 1914.

Application filed March 30, 1914. Serial No. 828,243.

To all whom it may concern:

Be it known that I, HENRI W. BILTZ, a citizen of the United States, residing at Kansas City, in the county of Jackson and 5 State of Missouri, have invented certain new and useful Improvements in Attachments for Mailing-Machines, of which the following is a specification.

My invention relates to attachments for 10 mailing machines, and my object is to provide a simple mechanism which may be adjusted, so that one or more stamps may be affixed to an envelop.

Heretofore, so far as I am aware, mailing 15 machines employed in sealing and stamping envelopes are capable of affixing but one stamp upon each envelop, hence, if two or more stamps are required they must be affixed by hand which occupies considerable 20 time where a large number of letters are to be mailed requiring more than one stamp each.

In the present instance after an envelop 25 has been run through the machine to affix the first stamp thereon, my attachment is adjusted to retard the stamp feeding mechanism the space of one stamp, so that when the envelop is run through the machine a second time the second stamp is affixed there- 30 to beside the first stamp. If a third stamp is to be affixed to the envelop my attachment is again adjusted the space of a stamp to further delay the feeding of the stamps, so that when the envelop is run through the 35 machine a third time, the third stamp will be affixed beside the second stamp, as will hereinafter appear.

In order that the invention may be fully 40 understood, reference will now be made to the accompanying drawings, in which:

Figure 1 is a broken plan view of a mailing machine provided with my attachment. Fig. 2 is a reduced irregular sectional view on line II—II of Fig. 1, with some of the 45 parts omitted. Fig. 3 is a plan view partly in section of the mailing machine with the upper portion thereof removed to more clearly show my attachment. Fig. 4 is a detail inverted plan view of my attachment 50 removed from the mailing machine. Fig. 5 is a similar view to Fig. 3, with some of the parts in different positions. Fig. 6 is an irregular section on line VI—VI of Fig. 3, with some of the parts removed. Fig. 7 is a 55 detail perspective of a pull-bar constituting part of my attachment.

For the sake of brevity I will describe only those portions of the mailing machine adjacent to and bearing more or less on the operation of my attachment.

1, 2, 3 and 4 designate feed rolls for feeding envelopes A, forward one at a time to sealing and stamping rolls 5 and 6, through a runway 7.

Roll 6 is fixedly mounted upon a constantly driven main shaft 8, carrying a loosely-mounted clutch member 9 which is driven by frictional contact with the roll 6. Clutch member 9 is intermittently engaged and held stationary by a pawl 10, normally 65 pressed by a coil spring 11 toward a pin 12 on said clutch member 9.

Pawl 10 is released from the pin 12 at intervals by an arm 13 fixed to the lower end of a vertical shaft 14, rockable in a bearing 15 and having the pawl 10 rigidly fixed to the upper end thereof.

9^a designates a large gear fixed upon the clutch member 9 to intermittently drive a pinion 9^b, for a purpose which will herein- 70 after appear.

16 designates an eccentric fixed upon the upper side of the gear 9^a and provided with a strap 17, secured to a pitman 18, connected to a stamp carriage 19, to impart recipro- 75

cable movement thereto. Carriage 19 is provided with pins or fingers 20 for feeding forwardly a ribbon of stamps B through a stampway 21, said fingers 20 being adapted to enter the usual perforations between the adjoining stamps. As the foremost stamp passes between the stamp feed rolls 22, which carry it against the envelop to which it is later affixed by the sealing rolls, said foremost stamp is severed by shears, not shown, from the ribbon which remains stationary until again fed forward by the carriage 19. One of the stamp feed rolls 22 is driven by the pinion 9^a and in turn drives the companion rolls 100 through a train of gears 22^a.

I will now proceed to describe the mechanism constituting the present invention.

23 designates a plate to which the several parts of my attachment are secured, said plate being in turn rigidly secured to the mailing machine at a point adjacent the rolls 4 and 6.

24 designates a finger which times the movement of the stamps B with relation to the envelops, so that one, two, three, or more stamps may be consecutively affixed to

each envelop, as will hereinafter more clearly appear. Said finger 24 normally extends across the path of each envelop, as disclosed by Fig. 3, and is pushed thereby to the right and backward, as disclosed by full and dotted lines, Fig. 5, where it is detained by the envelop until the same passes to the right, when said finger immediately springs forward across the path of the following envelop to the normal position disclosed by Fig. 3.

The finger 24 is provided at its outer end with an anti-friction roller 25, so that the passage of the envelops thereby will be attended with but little friction, and said finger 24 is slidably mounted upon a cam 26, to which it is connected by a pin or screw 27 slidably mounted in a slot 28 in said cam. Finger 24 is normally held forward in the path of the envelops, as disclosed by Fig. 3, by a lever 29 rockably mounted upon a fulcrum 30, secured to the cam 26, and normally held in the position disclosed by Fig. 3 through the intermediacy of a retractile spring 31, secured to one end of said lever and a pin or screw 32 projecting from the cam 26.

Cam 26 is normally held against a stop or shoulder 33 on a pull-bar 34 by means of a spring 35, having its free end bearing forward against screw 32 and its opposite end coiled about a pivot 36, upon which the cam 26 is rockably mounted. Pull-bar 34 is provided with a cable 34^a, extending to within convenient reach of the operator when the latter is feeding envelops to the machine.

Pivot 36 is slideable in a slot 37 near the inner margin of the plate 23, and projects through a dog 38 extending downward from the pull-bar 34 and beneath the plate 23, to assist the screw 36 in slidably holding the pull-bar 34 upon the plate 23. Dog 38 also coacts with a ratchet-bar 39, slideable against the underside of plate 23 and provided in the present instance with shoulders 40 and 41 for engagement with said dog. Ratchet-bar 39 is mounted at one end upon a pivot 42, and pivotally connected at its opposite end to a handle 43, extending through a guide 44 and connected to one end of a retractile spring 45, whereby said handle 43 is caused to hold the ratchet-bar 39 in yielding engagement with the dog 38. Dog 38 is normally drawn backward against one of the shoulders of the ratchet-bar 39 by a toggle 46, connected at one end by a pivot 47 to the dog 38 and connected at its opposite end to the underside of the plate 23 by a pivot 48. Toggle 46 is normally drawn backward by a retractile spring 49, connected at one end to said toggle and at its opposite end to a pin or screw 50 projecting from the underside of the plate 23.

Arm 13 is controlled by a lever 51, pro-

vided at its free end with a pin 52 projecting upwardly therefrom to engage the free end of said arm 13. The opposite end of lever 51 is mounted upon a fulcrum 53, projecting from the upper side of the plate 23. 70

Lever 51 is held in engagement with the adjacent end of the cam 26 by a spring 54 coiled around the fulcrum 53 and secured at its ends by screws 55 and 56, projecting from said lever 51 and the upper side of 75 the plate 23, respectively.

The operation briefly stated is as follows: As an advancing envelop impinges against the finger 24 the same is pushed to the right and backward out of the path 80 of said envelop, as disclosed by full and dotted lines Fig. 5, and retained in the dotted position until the envelop clears the roller 25 when said finger is immediately restored to the initial position disclosed by 85 Fig. 3, through the intermediacy of the springs 31 and 54 and the parts controlled thereby. When the finger 24 is tilted to the second position disclosed by full lines, Fig. 5, it rocks the cam 26 and causes it to swing 90 the lever 51 backward, so that it in turn swings the arm 13 backward and causes it to release the pawl 10 from the pin 12. When the pin 12 is thus released, the clutch 91 member 9 is immediately rotated by the 95 main roll 6 and in turn drives the gear wheel 9^a, which through the intermediacy of the train of gears 9^b, 22^a, drives the stamp feed 100 rolls 22. Rotation of the gear wheel 9^a, rotates the eccentric 16, causing the pitman 105 18 to move the carriage 19 forward until the forward end of the stamp ribbon B is seized by the initial rolls 22 and carried forward by the last roll 22 and the main roll 6 into engagement with the advancing envelop, to which it is affixed by said main roll 6, the roll 5, and other rolls not shown, in the rear of rolls 5 and 6. As the carriage 19 reaches the end of its forward 110 stroke, the forward stamp is severed from the ribbon B by the shears, and the carriage returns to the end of its backward stroke, at which time the finger 24 resumes its initial 115 position and permits the pawl 10 to engage the pin 12, and thus hold the clutch member 9 and the parts controlled thereby stationary until the finger 24 is again tilted to its second position by another envelop. When 120 an initial stamp is to be placed on each envelop, the pull-bar 34 is drawn in the direction of arrow a, Fig. 1, to adjust the dog 38 against the initial shoulder 40 of the ratchet-bar 39. This operation adjusts the finger 24 in the direction of the advancing envelop, so that the same will trip said finger in time to permit the initial stamp C to be affixed to the forward upper corner of 125 said envelop, as disclosed by Fig. 8. After one stamp has been affixed to each envelop and it is desired to apply a second stamp to 130

130

each envelop, the handle 43 is pulled in the direction of arrow *b*, Fig. 4, to allow the dog 38 to move back into engagement with the second shoulder 41 on the ratchet-bar 39. This operation carries the finger 24 to the right one step equal to or slightly greater in length than the width of a stamp, thus retaining the forward feeding of the stamp ribbon, so that the second stamp D 10 will meet the envelop just in the rear of the initial stamp C, where it is affixed to said envelop. A third stamp E may be affixed to each envelop beside the stamp D, by again running the envelops through the machine after the finger 24 has been drawn to the right another step by adjusting the dog 38 back upon the surface 39^a of the ratchet-bar 39. From the foregoing it will be understood that the number of stamps 20 which may be affixed to each envelop is limited only by the number of shoulders on the ratchet-bar 39.

While I have shown and described my attachment as applied to a mailing machine, it is obvious that it may also be applied to a mail canceling machine for the purpose of adjusting the stamp canceling devices to cancel one or more stamps affixed to mail matter.

Having thus described my invention, what I claim and desire to secure by Letters Patent is:

1. In a machine of the character described, a stamp feed carriage, a mail-matter controlled mechanism to time the movements of said carriage, and means to adjust said mechanism to change the time of movement of the carriage.

2. In a machine of the character described, a stamp feed carriage, a mail-matter controlled finger to time the movements of said carriage, and means to adjust said finger to change the time of movement of the carriage.

3. In a machine of the character described, a stamp feed carriage, a mail-matter controlled element, a cam carrying said element and adapted to time the movements of said carriage, said cam being actuated by said element, and means to adjust said cam to change the time of movement of the carriage.

4. In a machine of the character described, a stamp feed carriage, a mail-matter controlled element, a lever controlled by said element and adapted to time the movements of said carriage, and means to adjust said element to change the time of movement of the lever.

5. In a machine of the character described, a stamp feed carriage, a mail-matter controlled element to time the movements of said carriage, a dog for holding said element at different points of adjustment, and means for securing said dog at different points of its adjustment.

6. In a machine of the character described, a stamp feed carriage, a mail-matter controlled element to time the movements of said carriage, a dog for adjusting and holding said element at different points of its adjustment, and a ratchet-bar for securing said dog at different points of its adjustment.

7. In a machine of the character described, a stamp feed carriage, a mail-matter controlled element to time the movements of said carriage, a dog for adjusting and holding said element at different points of its adjustment, a ratchet-bar for securing said dog at different points of its adjustment, and a handle for disengaging said ratchet-bar from the dog.

8. In a machine of the character described, a stamp feed carriage, a mail-matter controlled element to time the movements of said carriage, a dog for adjusting and holding said element at different points of its adjustment, a spring-retracted toggle to adjust said dog in one direction, and means coacting with said dog to hold it at different points of its adjustment.

9. In a machine of the character described, a stamp feed carriage, a mail-matter controlled element to time the movement of said carriage, a dog for adjusting and holding said element at different points of its adjustment, a spring-retracted toggle to adjust said dog in one direction, a pull-bar to adjust said dog in another direction, and means coacting with said dog to hold it at different points of its adjustment.

10. In a machine of the character described, a stamp-feed carriage, a mail-controlled element, a cam on which said element is slidably mounted, a spring-retracted lever to normally hold said element at one end of its adjustment, a plate on which said cam is slidably and rockably mounted, its rockable movement being controlled by the element, manual means for sliding the cam upon said plate, and a lever controlled by said element and adapted to time the movements of said carriage.

In testimony whereof I affix my signature, in the presence of two witnesses.

HENRI W. BILTZ.
